(57) **CLAIM**

The ornamental design for a convertible pickup canopy, as shown and described.

DESCRIPTION

FIG. 1 is a rear perspective view of the convertible pickup canopy of the present invention, the convertible pickup canopy shown in an expanded condition and attached to a bed of a pickup truck;

FIG. 2 is a rear elevational view of the of the convertible pickup canopy of the present invention, the convertible pickup canopy shown in an expanded condition;

FIG. 3 is a front elevational view of the of the convertible pickup canopy of the present invention, the convertible pickup canopy shown in an expanded condition;

FIG. 4 is a left side elevational view of the convertible pickup canopy of the present invention, the convertible pickup canopy shown in an expanded condition;

FIG. 5 is a right side elevational view of the convertible pickup canopy of the present invention, the convertible pickup canopy shown in an expanded condition;

FIG. 6 is a top plan view of the convertible pickup canopy of the present invention, the convertible pickup canopy shown in an expanded condition;

FIG. 7 is a bottom plan view of the convertible pickup canopy of the present invention, the convertible pickup canopy shown in an expanded condition;

FIG. 8 is a rear perspective view of the convertible pickup canopy of the present invention, the convertible pickup canopy shown in a collapsed condition;

FIG. 9 is a rear elevational view of the of the convertible pickup canopy of the present invention, the convertible pickup canopy shown in a collapsed condition;

FIG. 10 is a front elevational view of the convertible pickup canopy of the present invention, the convertible pickup canopy shown in a collapsed condition;

FIG. 11 is a left side elevational view of the convertible pickup canopy of the present invention, the convertible pickup canopy shown in a collapsed condition;

FIG. 12 is a right side elevational view of the convertible pickup canopy of the present invention, the convertible pickup canopy shown in a collapsed condition;

FIG. 13 is a top plan view of the convertible pickup canopy of the present invention, the convertible pickup canopy shown in a collapsed condition; and,

FIG. 14 is a bottom plan view of the convertible pickup canopy of the present invention, the convertible pickup canopy shown in a collapsed condition.

The broken line showing of environment is for illustrative purposes only and forms no part of the claimed design.
